ATTORNEY

UNITED STATES PATENT OFFICE

CARL M. LIEBER, OF OKLAHOMA CITY, OKLAHOMA

INSTANTANEOUS AUTOMATIC WATER HEATER

Application filed June 24, 1929. Serial No. 373,428.

My invention relates to instantaneous automatic water heaters designed for the instant heating and delivery of an intermittent or continuous flow, of water.

5 The object of my invention is to provide a device where the water to be heated passes through a series of sections formed in two columns, the water entering the lower section of one column and passing upwardly 10 through the series of sections in that column and then over to the top of the second column and downwardly through the series of units in the second column and then to use.

In so far as this applicant knows or can 15 ascertain, instantaneous water heaters of present use are not adaptable to circulatory systems unless provided with an expensive auxiliary storage tank. They are given to excessive sweating, to an extent which requires 20 shielding of the gas flame, the provision of a drip pan and, frequently, the added provision of a drain pipe connected to the sewer or other outlet.

My device consists substantially of a plurality 25 of water receiving units, connected in series, through which the water circulates and in which the water is heated. The units are so disposed that the cold water enters the first unit which is disposed directly above the flame and after passing through this unit it rises to other units thereabove. After the water has passed through the top unit of the heater, it enters another unit which is disposed in the upper part of the heater and from this last mentioned unit the water circulates 30 downwardly through a plurality of like units and finally enters the lowermost unit which is also directly above the flame. From this last mentioned unit, the water is conveyed to the faucet. By this arrangement the cold water can not condense moisture from the gases within the heater because of the fact that the first unit is disposed within 35 the flame and that the second unit thereabove is sufficiently close to the flame to prevent condensation by the water which has previously had the chill removed when it passed through the first unit. As the water rises through the next succeeding units its temperature is 40 raised and as it descends through the last

units it has reached an extremely high heat. It is a known fact that condensation within a heater takes place more abundantly in the upper part thereof. By the time the water in applicant's heater has reached the upper portion thereof its temperature has been so raised that condensation is prevented.

Instantaneous water heaters of present use are provided with complicated automatic control devices, some of the moving parts 60 of which are operative under water and consequently are subject to the water's corrosive action and to the collection of the water's precipitate. Such corrosion and precipitate collection tend to render such moving parts 65 sluggish in action or wholly inactive. Thus the feature of automatic control is lost. The use of packing glands, in such heaters, is always attended with more or less trouble, the necessity of frequent adjustment or renewal 70 of the packing element, the tendency to leak if adjusted too loosely, and the liability of remaining inoperative if adjusted too tightly. In the automatic controls of my device, no 75 packing glands are used, water contacts no moving part of my thermostatic control and no moving part of the water pressure gas control other than the inside of the sylphon.

In my device, the installation of drip pans and drain pipes to receive and to carry off 80 the drip from condensation is unnecessary as is also the use of an auxiliary storage tank, when a circulatory system is desired. The easily removable front and back panels of my device, the accessibility of the interchangeable heat transmission units, and the ease with which same may be removed and cleaned, are features extremely advantageous. It is my belief that my device overcomes 85 all these disadvantages of other instantaneous automatic water heaters of present use and, moreover, has many novel, useful and practical features of its own.

With these and other objects in view as will 90 more fully appear my invention consists in the construction, novel features, and combination of parts hereinafter more fully described, pointed out in the claims hereto appended, and illustrated in the accompanying 95 two-sheet drawings, of which,

Figure 1 is a side elevational view of my device showing the gas feed line externally thereupon;

Figure 2 is a front elevational view showing the inlet and outlet water lines and the gas line, all connected thereto;

Figure 3 is a fragmentary top sectional view of one of my heat transmission units;

Figure 4 is a sectional end view of one of 10 the heat transmission units;

Figure 5 is a side view of one of the two plates which form the main body of the heat transmission units shown in Figures 3 and 4;

Figure 6 is a side elevational view of the 15 plurality of heat transmission units and their arrangement for circulatory effect;

Figure 7 is an elevational view of the pilot light, the gas burner, and in section, a part of the gas feed line;

20 Figure 8 shows, above, a sectional side view of the water pressure gas control; and below, a sectional side view of the thermostatic gas control;

Figure 9 is a fragmentary perspective view 25 showing the terminus of the circulatory return line and the disposition of the thermostatic control element.

Like characters of reference designate like parts in all the figures.

30 It is understood, that various changes in the form, proportion, size, shape, weight and other details of construction, within the scope of my invention may be resorted to without departing from the spirit or broad

35 principle of my invention and without sacrificing any of the advantages thereof; and it is also understood that the drawings are to be interpreted as being illustrative and not restrictive.

40 A practical embodiment of the invention as illustrated in the drawings includes:

A metal cabinet 1, disposed upon an angle iron frame, not shown, and housing principally a gas burner 2, a pilot 3, a plurality 45 of heat transmission units 4, together with their connecting nipples 5, a thermostatic element container tube 6, a portion of the cold water inlet pipe 7 and a portion of the hot water outlet pipe 8, having a usual relief valve 102.

50 Upon the outside of said cabinet 1 is disposed the main gas line 9 leading to the said burner 2, through an automatic water pressure gas control 11 and thence through an automatic thermostatic gas control 12. The pilot line 10 leading to pilot 3 is a takeoff from gas lead 9 above said controls 11 and 12. Also externally upon the cabinet 1, is the drain cock 13, the connection for a return hot water line 14, a vent 15 to the flue, the down draft hood 16, and the outward extensions of the said inlet and outlet cold and hot water lines 7 and 8.

55 The said cabinet 1 rests upon a plurality of legs 17, has a flat removable panel back

the edge of which is shown at 65, and a flat removable panel front 18, provided at its lower portion with a removable door panel 19 secured in place by any usual means such as two ordinary buttons 20. The said door panel 19 has in its lower portion, a rectangular aperture shown as 21. Said cabinet 1 is also provided with flat rectangular sides 22 and 23, each provided at its lower portion with a plurality of circular apertures shown as 24. Said cabinet 1 has a flat top which is centrally provided with the flue vent 15, before mentioned. The bottom of said cabinet is closed by a removable shallow pan indicated by the dotted lines at 25.

70 Within the cabinet 1 and immediately above said pan 25 is provided the said gas burner 2, of any known or desired design, but which at this time I conceive as preferably of the type known to the art as the Bunsen burner, and which comprises a sufficient number of individual burners 100 to render efficient my device with respect to heating a desired number of gallons of water per minute. The gas flow to this burner is provided through the said gas feed line 9, but before reaching said burner 2 the gas must first pass through the said automatic water pressure gas control 11 and thence through the said automatic thermostatic gas control 12, disposed the one above the other upon the said feed line 9, attached to a usual source of gas supply.

75 The said water pressure gas control 11 for which a patent application is being filed by this inventor, practically simultaneously herewith, is disposed partly within and partly without the said cabinet 1, adjacent said cabinet's top portion and the said side 22. Within the vertical portion of a T 26 upon the said cold water feed line 7, and within said cabinet 1, I provide a frustum shaped jet member 27, the wide upper end of which is open to cold water flow, its other and smaller end 28 having a smaller opening shown as 29. Said smaller jet end 28 does not fully 80 close the lower continuation of the said pipe line 7, but leaves an annular opening shown as 30 between the external sides of said jet end 28 and the internal wall of the enveloping continuation of said feed line 7. The said 85 annular opening 30 permits a flow of water, when same is under pressure, both above and below said jet end 28, to back up through said annular aperture 30, and to fill a small pressure chamber indicated as 31, in that section of the said control unit 11 which extends through said side 22 and is threaded to receive into the stem of the said T 26. The said pressure chamber 31 leads, at its other end, into a sylphon 32 which is wholly contained within a gas chamber shown as 33 in said control unit 11. Said sylphon 32 is provided at one end with an annular flange 35 which is hermetically secured to the inside wall of the plate 34 which constitutes one of the cast-

ings of the said control unit 11. At its opposite end, said sylphon 32 contacts the head of a usual valve 36 which is designed to open and close a port, shown as 37, for the passage 5 of gas from said chamber 33 downwardly through bore 43 to said gas burner 2. Said valve 36 is provided with a stem 38, extending oppositely to said sylphon, and said valve 36 is kept in constant contact with said sylphon by the pressure of a compression spring 39, the pressure of which is regulated by a threaded screw 40. The upper portion of said gas chamber 33 opens directly, through a port shown as 41, into the upper bore 42 15 of said control unit 11.

The said bore 43 is threaded to receive a pipe line also indicated as 9 for the further conduct to said thermostatic control unit 12, of the gas which has been permitted to flow 20 through said water pressure control 11. Between said controls 11 and 12 I provide an ordinary manually operative cut-off valve 44.

Said thermostatic control unit 12, for which an application for patent is being filed 25 practically simultaneously herewith, by this applicant said application being dated June 24, 1929, Serial Number 373,427, comprises two principal flanged members 45 and 46, designed to be hermetically held together by a plurality of removable bolts 47, as best shown 30 in Fig. 1. Said flanged member 45 is provided with an inlet bore 48, threaded at its upper portion to receive a section of the said feed line 9, and thus to receive incoming gas. Said member 12 is also provided with an outlet bore 49 threaded at its lower portion to receive another section of said feed line 9 for the further transmission of such gas as has been permitted to flow through said 40 member 12. Said member 46 is provided, outstanding perpendicularly from its central portion, with a hollow cylindrical extension 50 which is threaded, as shown at 51, for connection with a T coupling 52. That portion 45 of said arm 51 which extends into said T 52 is provided with a smaller tube 6 brazed thereto and extending therefrom and previously mentioned as the thermostat tube. Said thermostat tube 6 is closed at its free end 50 53 and at its other end portion opens into the bore, shown as 54, of the said arm 50. The said bore 54 at its other end is hermetically sealed by a thin diaphragm 55. Said thermostat tube 6 and said bore 50 form a 55 chamber which is filled with a volatile fluid or gas under pressure, such as ether or the like. The bolting together of the said members 45 and 46 forms a gas tight chamber shown as 56. Into said chamber 56 there is 60 a port shown as 57 from said inlet bore 48 and an outlet port shown as 58 leading to said gas outlet bore 49. No means is provided for closing said inlet port 57, but said outlet port 58 is designed to be automatically opened and 65 closed by a valve 59. An adjusting screw 60

and a compression spring 61, contacting the end of the stem 62 of the said valve 59, provide the means for manually regulating the tension of said valve 59 in its contact with the said diaphragm 55.

Said cold water feed line 7 should be provided with an ordinary water pressure regulator 101 and a usual check valve 63. Said line 7 enters my device at its top portion, passes downwardly through the said T 26, 75 thence downwardly and angularly to a T 64 adjacent the lower central portion of the back panel 65 of the said cabinet 1. From the said T 64 a short length of pipe leads outwardly through said back panel 65 to a drain cock 80 66. Through a nipple 67 the said T 64 is connected with the first of the plurality of said heat transmission units 4.

Said heat transmission units each comprise: 85 a rectangular casting 68, provided with a plurality of perforations shown as 69, laterally through its respective side portions 70 and 71 and its respective end portions 72 and 73. The said casting 68 is bulged outwardly over the greater portion of its length and width as shown at 74 and said bulged portion 74 is provided with a plurality of perforations shown as 75 in alignment therethrough. Said bulged portion 74 is also provided, extending upwardly from its top central portion, with a boss which is vertically bored. Said bore is threaded at its top portion to receive the lower end portion of one of said nipples 5, and the lower portion of said bore penetrates the upper central portion of said side casting 68 as shown at 77. Extending outwardly from, and perpendicularly to, said casting 68 are a plurality of thin tubes 78, of copper or the like, each having thereupon a plurality of fins 79. The heads of the said tubes 78 are hermetically beaded respectively into the plurality of said perforations 75. The free ends of said tubes 78 are each closed as shown at 80.

The said heat transmission units 4, each further comprises a casting 81, somewhat similar to said casting 68, designed to match and to be bolted to same through perforations aligned with said perforations 69. Casting 81 is also provided with a bored boss 82 similar to said bored boss 76, but extending downward from said casting 81, to be connected by the said nipple 67 to said T 64. Clamped or bolted between said castings 68 and 81 is a partition plate 83, which completely and tightly separates the chambers shown as 84 and 85, the one from another, except that said partition plate 83 is provided with a plurality of thin tubes 86 of copper or the like, which extend through said chamber 85, respectively, into the said tubes 78 to a point relatively close to the said tube ends 80. Said tubes 86 are open at their free ends and also open into said chamber 84 as shown at 88. Thus it may be seen that 110 115 120 125 130

cold water from the said line 7 entering chamber 84 through T 64, may be forced by the usual water pressure through the opening 88 into tubes 86, out of same through open end 87, back through the larger tubes 78 into chamber 85 and thence through the perforation 77, bored boss 76, through the said nipple 5, and so into and through each of the succeeding said units 4 above. The water passing through said top unit 4 is conducted through a connecting pipe 89 and into the opposite top unit 4, thence downwardly through the succeeding units 4, each of which is identical with said units 4 oppositely positioned therefrom, except that the position of each of said units 4 upon the down flow side is reverse to the position of each of said units 4 upon the up flow side. Passing through the lowermost of said down flow units 4, the water enters a pipe 90 thence passes through a T 92, a nipple 91 and enters the said T 52, which latter is best shown in Fig. 8. In said T 52 and in the pipe 93 extending therefrom, the water has a circulation around the said thermostat tube 6. Passing onward through said pipe 93 the water passes through a T 94, and thence upward and outward through the said hotwater outlet pipe 8, to the various hot water taps of the system, not shown. Said T 94 also receives one end of a nipple 95, which extends through the lower portion of the said cabinet side panel 23. The outstanding end of said nipple 95 is provided with the said hot water drain cock 18. The said T 92 beside serving as a connection for the return of hot water direct from the lowermost of said down flow hot water units 4 through said pipe 90, also furnishes a connection through the said nipple 14 and elbow 97 for a pipe line 98 which is returned from an outlying section or sections of the hot water distributing line. Said pipe line 98 is designed to serve as a medium for return circulation and is provided with a check valve 99 somewhat adjacent said T 92. It is understood that said return circulatory system is optional and not mandatory.

In describing the operation of my device as above, it will be presumed that all gas and water pipe connections have been properly made, that the device as a whole is connected for service with pilot light burning and all outlet water taps closed. Under these conditions the thermostatic control valve 59 will be open, due to cold water in the T 52 and the pipe 93. No gas, however, is flowing to the said thermostat unit 12, through said water pressure gas control unit 11. This is due to the fact that water pressure in the cold water feed line within the device has backed up through the annular opening 30 into the said chamber 31, causing a longitudinal distension of the syphon in said unit 11, and thus causing the valve

36 to close the port 37. With said port 37 closed no gas may flow through said unit 11 into the line below.

Upon the opening of a tap, however, connected at any point within the hot water outlet line 8, pressure is immediately and appreciably relieved in the interior feed line 7, due to the fact that the jet opening 29 is smaller than the faucet opening. The lessening of pressure in said interior feed line 7 is immediately reflected in the lessening of pressure in the said chamber 31, through said annular opening 30. With a lessened pressure in said chamber 31, the said valve 36 actuated by compression spring 39 upon valve stem 38, is opened against the lessened resistance of the sylphon 32 and gas is permitted to flow from the chamber 33 through the port 37 into the feed line 9 below. Passing on through the open unit 12, the gas in the burner 2 is ignited by the flame from the pilot 3. The flame from the multiplicity of said individual burner tubes 100 forming the said gas heater 2, directed in its greatest intensity upon the lowermost of the said thin heat transmission units 4, and to a greater or less extent upon those of said units 4 above, quickly heats the water therein which is carried upwardly by one tier of said units and thence across and downwardly by the opposite tier, as previously described, into said pipe 90, through said T 52, circulating around the said thermostat tube 6, on through the pipe 93 and out through said hot water outlet line 8 to the said open tap or taps. Upon the closing of the open tap, pressure from the open cold water feed line immediately backs up into the said chamber 31 as previously described, again distends the sylphon 32, closes the port 37 and shuts off the flow of gas to said unit 12 and consequently to said burner 2. In the meantime should the heat from the burner 2 become sufficient to heat the water to a temperature greater than that as previously determined, the excess of heat expanding the volatile liquid or gas in the said thermostat tube 6, causes a pressure upon the said diaphragm 55 which in turn causes the closing of the said valve 59 against the regulative pressure of the said compression spring 61. It will be apparent that the closing of the valve 59 will shut off the further flow of gas to said burner 2, and also that, due to the action of said compression spring 61, said valve 59 will again open when a lower temperature of the said thermostatic tube 6 permits again the condensation of the gases therein contained.

It will be readily understood that the hot water after leaving the last of said heat transmission units 4 and entering said pipe 90 will not be permitted to flow upward through the return line of the system be-

cause of the provision, as heretofore described, of said check valve 99.

In the construction of the heat transmission units it will be understood that not only are the walls of the inside and outside tubes very thin, offering the maximum of heat conductivity, but that the water flows therein between in a very thin sheet, and thus is quickly heated.

Obviously, the invention is susceptible of embodiment in forms other than that which is illustrated in the accompanying drawings and described herein, and applicable for uses and purposes other than as detailed, and I therefore consider as my own all such modifications and adaptations and other uses of the form of the device other than as herein described as fairly fall within the scope of my claims.

Having thus described my invention what is claimed and desired to be secured by Letters Patent, is:

1. In an instantaneous water heater having heating units each comprising pairs of tubes arranged in horizontal courses, each pair of tubes including an outer closed ended tube and an inner open ended tube enclosed by the outer tube, said tubes connected to a header arranged to deliver water to the inner tubes and to receive water from the outer tubes, the arrangement of said units in vertical columns in a manner whereby the water first enters the lowermost unit of one column, passes upwardly through the next succeeding units of that column thereabove, then passes into the uppermost unit of the next column and descends through each succeeding unit of the last mentioned column.

2. In an instantaneous water heater, the combination with a plurality of substantially horizontally disposed heating units, each of said units comprising pairs of tubes arranged in horizontal courses, each pair of tubes including an outer closed ended tube, an inner open ended tube, and a header connecting said tubes and arranged to deliver water to the inner tubes and to receive water from the outer tubes, of the arrangement of said units in vertical columns whereby the water first enters the lowermost unit of one column, passes upwardly through the next succeeding units of that column thereabove, then passes into the uppermost unit of the next column and descends through each succeeding unit of the last mentioned column.

3. In an instantaneous water heater, the combination with a plurality of heating units substantially horizontally disposed within a housing above a heat generating element, each of said units comprising pairs of tubes arranged in horizontal courses, each pair of tubes including an outer closed ended tube, an inner open ended tube, and a header connecting said tubes and arranged to deliver water to the inner tubes and to receive water

from the outer tubes, of the arrangement of said units in vertical columns whereby the water first enters the lowermost unit of one column, passes upwardly through the next succeeding units of that column thereabove, then passes into the uppermost unit of the next column and descends through each succeeding unit of the last mentioned column.

4. Organization as described in claim 1, in which the tubes of each of said columns of units extend toward each other.

5. Organization as described in claim 3, in which the tubes of each of said columns of units extend toward each other, and in which the tubes of the lowermost unit of each column is located directly above said heat generating element.
